United States Patent Office

Des. 233,548
Patented Nov. 5, 1974

233,548

CURTAIN FABRIC

Peter E. Schroeder, Oberwil, near Brenngarten, Switzerland, assignor to Gardisette International AG, Lucerne, Switzerland

Filed May 22, 1973, Ser. No. 362,815

Claims priority, application Germany Feb. 20, 1973

Term of patent 14 years

Int. Cl. D5—02

U.S. Cl. D47—6 E

The single figure is a plan view of a curtain fabric showing my new design, the dark background being for purposes of illustration only.

I claim:

The ornamental design for a curtain fabric, as shown and described.
